UNITED STATES PATENT OFFICE

2,184,932

MOTOR

Wade H. Wineman, Michigan City, Ind., assignor
to Sullivan Machinery Company, a corporation
of Massachusetts

Application September 17, 1935, Serial No. 40,949

31 Claims. (Cl. 121—150)

My invention relates to expansible chamber motors, and more particularly to expansible chamber motors of the type especially adapted for pumping and similar uses. In certain oil fields where there is available a considerable quantity of oil but insufficient pressure in the strata to cause the oil to rise to the surface, steam or pneumatically operated, single-acting pumping motors have been used to great advantage for actuating through a suitable pump rod line pumps arranged down in the oil wells. Such pumping motors are commonly, though not always, arranged in groups adjacent a central source of operating pressure fluid supply, and individual pumps are not attended continuously by pump runners. As a result it is imperative to make the pumping motors as nearly completely automatic and self-protective as possible.

It is an object of the present invention to provide an improved expansible chamber motor. It is another object of my invention to provide an improved expansible chamber motor having improved distributing valve means. It is a further object of the present invention to provide an improved expansible chamber motor having improved means for preventing breakage in the event that the motor loses its load suddenly. It is still another object of the present invention to provide an improved automatic vent check valve 5 in association with an expansible chamber motor for the purpose of protecting the same against breakage in the event of over-stroking, while at the same time interfering practically not at all with the normal operation of the motor. Other objects and advantages of the invention will hereinafter more fully appear.

In the accompanying drawings, in which for purposes of illustration one embodiment which the invention may assume in practice has been shown,

Fig. 1 is a side elevation of a pumping motor cylinder in which my invention is embodied in an illustrative form,

Fig. 2 is a view partially in side elevation and partially in central vertical section through the pumping motor of Fig. 1,

Fig. 3 is a horizontal section on an enlarged scale on the plane corresponding to line 3—3 of Fig. 2, showing the distributing valve in exhaust position,

Fig. 4 is a similar view showing the distributing valve mechanism in admission position,

Fig. 5 is an enlarged fragmentary sectional view on the same planes as Figs. 3 and 4, showing

details of the distributing valve control mechanism,

Fig. 6 is an enlarged central vertical section through the vent check valve mechanism,

Fig. 7 is a fragmentary section through the cylinder wall on the plane of the section line 7—7 of Fig. 2.

Referring first to Fig. 1, it will be observed that suitable supporting means 2 carries a motor device 3 which comprises an upper head member 4, 10 a lower head member 5, and a cylinder member 6. The cylinder 6 has a bore 7 in which a piston 8 is reciprocable, and a piston rod 9 connected to the piston 8 is adapted to be connected to a pump rod line. The piston 8 is a single-acting 15 piston and is adapted to be raised by pressure fluid admitted beneath the same and to be moved downwardly upon a reduction in the pressure beneath the piston by the weight of the pump rod line, its own weight, etc. The lower cylinder 20 head 5, which is connected to the upper head 4 by a series of tie rod devices 10, is provided with a valve chest and supply and discharge connection generally designated 12. This comprises a motive fluid supply space 13 to which fluid is 25 supplied through a supply connection 14, of which but a fragment is shown. It also comprises an exhaust connection 15 which is connected to an exhaust connection 16, of which but a fragment is shown. The fluid supply may be at a pressure 30 of 200 or 300 pounds per square inch, for example, and the exhaust connection is maintained by suitable means, not shown, under a back pressure of perhaps 75 to 100 pounds, the pressure used depending upon the operating conditions. A 35 connection 17 leads to the bottom of the cylinder bore 7. The supply space and the cylinder port 17 are separated by septum 19, and the exhaust space 15 and cylinder port 17 are separated by septum 20. A suitable valve-chamber-forming 40 element 21 is mounted in a series of bores of progressively decreasing sizes 22, 23, 24, 25, and is provided with shoulders as at 26 adapted to seat upon supporting surfaces 27, and is secured in position in any suitable manner. A head 28 held 45 in position by screws 29 is arranged opposite the valve chest member 21, and has a reduced portion 30 which extends into the bore 31 of the valve chest member. It will be noted that the valve chest member is not a close fit at 32 at its exhaust end for the member 12, and a connection 33 connects the exhaust space 15 with the exhaust end of the bore 31. The bore 31 is connected by ports 34 with the exhaust space, by ports 35 with the cylinder port, and by ports 36 with the supply 50

55

space 13. Within the bore 31 a valve element 40 is reciprocably mounted. This includes a suitably ringed head 41 connected by a reduced portion 42 with another ringed portion 43, the portions 41 and 43 fitting the bore 31. Beyond the portion 43 the member 40 has an enlarged head 44 which fits in an enlarged bore 45 aligned with the bore 31. The space 45 at its end nearer the bore 31 may be suitably vented, if desired.

10 It will be noted that between the portions 41 and 43 there is provided a distributing groove 47 which, in the position of the parts shown in Fig. 4, connects the ports 35 and 36 and enables the admission of fluid beneath the motor cylinder. 15 In the position of the parts shown in Fig. 3 the space 47 connects the cylinder port 17 with the exhaust.

Since the exhaust space 15 is maintained under a substantial back pressure as above noted, it 20 will be evident that there will always be a substantial pressure acting upon the exhaust end of the valve piston portion 41, and, accordingly, in the absence of counter-pressures, the valve member 40 will occupy the position shown in 25 Fig. 4. Suitable means is provided for periodically moving the valve member 40 out of that position into the position shown in Fig. 3, and for maintaining it in the latter position for the necessary periods. Referring to Figs. 1 and 2, 30 it will be observed that a suitable connection 50, whose upper end may be connected at any one of a series of positions 59' to the bore of the cylinder, at its lower end is connected through a coupling 51 to a central passage 52 formed in a 35 sleeve member 53, supported in a cover member 54 for the valve chest 21. At its inner end the member 53 provides a conical seat 55 with which a conical tip 56 upon a spring-pressed plunger 57 mounted within a retaining plug 58 is adapted 40 to engage. It will be noted that the spring 59 which acts upon the lower end of the member 57 normally maintains the latter projected a certain distance beyond the end surface 60 of the valve head 43, and that when the valve member 45 40 is in the position shown in Fig. 4 portion 56 seats in and effects a seal with the conical recess 55. Accordingly, since the spring 59 is of such strength as to prevent unseating of the valve portion 56, even by full cylinder pressure, when 50 the valve member 40 is in its position of Fig. 4, it will be requisite for the valve member 40 to move a short distance from the position shown in Fig. 4 before the space within the cylinder bore 7 will be placed in free communication with the surface 60, through the passage 50.

It will also be noted that a suitable connection 62, which may be connected as desired through different ones of a series of openings 62' with the cylinder bore 7 near the upper end of the latter, 60 leads to a connecting plug 63 which holds a valve-receiving chamber member 64 in position in the head 54. Within the member 64 is a spring 65 which presses a tapered valve element 66 having a projecting stem 67 normally to its seat 68. 65 Passages 69, sealed when the valve 66 is on its seat 68, afford, when the valve 66 is unseated, a connection between the passage 62 and the main valve surface 60, such connection being via a passage 70 in the plug 63, the bore through the member 64, the passages 69 in the valve, and around the stem 67 of the latter, there being clearance at that point.

The spring 65 is of such strength as normally to maintain the stem 67 projected into the space 75 in which the distributing valve head 44 moves

and concurrently maintain the valve 66 on its seat. When the valve 40 is moved to the position of Fig. 4 its surface 60 will engage the stem 67 and move the valve 66 to open position and hold it there with the surface 60 in communication with the passage 62, and so with the cylinder bore 7 at the point 62' to which the connection 62 is connected. It will be understood, of course, that all the inactive connection points 50' and 62' will be sealed by suitable plugs. 10

The cylinder member 6 is provided with a series of by-pass passages or enlargements 75. These, it will be noted, provide a series of circumferentially arranged, longitudinally extending clearances so that the piston 8 may travel substantially freely between the ends of these by-passes. Above the upper end of the by-passes the end of the cylinder may be largely or completely sealed, as may be desired. 15

To permit downward movements of the piston 20 without retardation due to sub-atmospheric pressure above the piston, I provide suitable means for admitting pressure fluid to one of the by-pass connections, and also provide means for permitting substantially unrestricted discharge through 25 said same connection so long as the piston moves at a normal rate, but such means is made operative to provide a retardation to the travel of the piston whenever the piston movement in its working direction is at an excessive rate. It will 30 be observed that one of the by-pass spaces 75 is connected through a connection 71 with a valve body 78 whose interior is divided by a septum 79 into two chambers, respectively 80 and 81, chamber 80 communicating with the cylinder 35 bore and chamber 81 communicating through a pipe 82 with an air cleaner 83. A port 84 in the septum 79 provides a seat 85 for a check valve 86 whose stem 87 normally rests upon an adjustment screw 88 which may be positioned to permit 40 the valve 86 to be off of its seat normally at all times by any predetermined desired amount. A small port 89 connects the chambers 80 and 81. Valve 86 will not be adjusted to a position in which an abnormal rush of fluid through the 45 connection 71 may not lift it to its seat.

The mode of operation of the entire apparatus may now be briefly described. Starting with the piston in the position shown in Fig. 2 and with the valve 40 in the position shown in Fig. 4, it 50 will be noted that motive fluid supplied through the connection 14, chamber 13, ports 36, valve groove 47, and ports 35 and cylinder port 17, will pass beneath the piston 8 and move the latter upwardly. As the piston moves up it will first 55 place in communication with the cylinder bore 7 the upper end of the connection 50, but no fluid under cylinder pressure will pass through the connection 50 to act upon the distributing valve surface 60, because the valve element 56 will, 60 in the position of the parts in Fig. 4, rest upon the seat 55 and preclude such flow. The piston 8 will, therefore, continue its upward movement under continued supply of motive fluid until the lower end of the piston 8 passes above the 65 active opening 62' and permits the ingress of cylinder pressure to the connection 62. During this normal piston travel described the air above the piston will be displaced readily through the connection 89 and through the passage 34, 70 primarily through the latter of course. When the connection 62 has been brought into communication with the cylinder bore, cylinder pressure will pass therethrough, through the passage 70, through the port 69 in the then unseated valve 75

66, around the stem 67, and act upon the surface 60 and force the valve 40 sufficiently far toward the position of Fig. 3 so that the valve 56 will unseat. It will be understood that the valve 56 should unseat before the valve 66 seats. Thereupon, although the valve 66 will promptly seat, pressure will flow from the cylinder bore through the connection 50, connection 51, passage 52, and into the bore 45, and move the valve 49 into the position shown in Fig. 3. Although the space below the piston will be connected to the exhaust space when the valve is shifted, it will be noted that the pressure transmitted to the surface 60 will be higher at least 15 until the valve is fully thrown than the exhaust pressure, and moreover it will be observed that the surface 60 is larger than the area of the head 41 exposed to an exhaust pressure, and so the valve 49 will be maintained in the position of Fig. 20 3 throughout the exhaust stroke of the piston 8. As soon as the lower end of the cylinder bore 7 is connected through the passage 17, ports 35, groove 47 and ports 34 to the exhaust space 15, the weight of the parts supported by the piston 8 25 will move the latter downwardly and force out the motive pressure beneath the piston against the back pressure. It will be appreciated that during the downward stroke of the piston 8, air will pass into the upper end of the cylinder bore 30 through the connection 82, past the valve 86, and somewhat through the port 89 and through the connection 17, into the cylinder bore. When the upper end of the piston 8 places the connection 62 in communication with the atmosphere through the air connections just mentioned, nothing will happen, for the spring 65 is of sufficient strength to maintain the valve 66 seated when not positively unseated by movement to the position of Fig. 4 of the valve member 40. The piston 8 will, therefore, move downwardly 40 until its upper end uncovers the mouth of the connection 50, and when that occurs venting of the space between the surface 60 on the valve 40 and the valve chest head 54 will occur, and since this venting is to "atmosphere" the back pressure which acts upon the relatively large area of the head 41 will promptly move the valve 40 to the position shown in Fig. 4 again, and when the valve 40 reaches that position, valve 56 will 45 seat and valve 66 will be unseated, and the motor will be ready to make another working stroke in the manner described.

In the event that the pump rod breaks, or the pump packing ruptures, it will be understood that the piston 8 will be freed of its load to such an extent that its upward movement will be at a much higher rate than its normal rate of movement. Therefore, there will be a much more rapid compression of the air above the piston and a tendency of the air to rush more rapidly through the connection 17. This will cause the valve 86 to be raised to its seat, and the only venting then possible will be through the passage 89, and there will, therefore, be an early commencement of cushioning of the upward movement of the piston 8 and after the piston travels above the by-pass passage 75 there will be entrapped above it air already at considerably above atmospheric pressure (for it will be understood that cylinder pressure which will not have had time to be reduced to exhaust line pressure can also pass the piston as the latter is traveling between the ends of the by-passes), and the piston will be brought to rest without damage.

75 From the foregoing description it will be ap-

preciated that I have provided a highly efficient apparatus for a wide number of purposes, and particularly for the performance of pumping operations in oil fields of the character described. It will be noted that the parts are simple, that there is no possibility of the valve mechanism ever operating to connect the supply and exhaust connections due to incomplete operation, that breakage of the parts due to blowing out of the packing, or breaking of the pump line, is very effectually prevented, and that the whole apparatus is rugged and absolutely positive in its operation.

While I have in this application specifically described one form which my invention may assume in practice, it will be understood that this form of the same is shown for purposes of illustration, and that the invention may be modified and embodied in various other forms without departing from its spirit or the scope of the appended claims.

What I claim and desire to secure by Letters Patent is:

1. In a motor, in combination, a cylinder, a piston reciprocable therein, means for continuously venting one end of said cylinder, and means for controlling admission and exhaust with respect to the opposite end of the cylinder including a valve performing both admission and exhaust functions and throwing means for said valve including means for continuously subjecting one end thereof to motor back pressure, said back pressure being in excess of atmospheric pressure, and means for alternatively subjecting the other end thereof throughout nearly complete piston 30 travels in opposite directions to cylinder pressure and to atmospheric pressure.

2. In a motor, in combination, a cylinder, a piston reciprocable therein, means for continuously venting one end of said cylinder, and means 40 for controlling admission and exhaust with respect to the opposite end of the cylinder including a valve performing both admission and exhaust functions and throwing means for said valve including means for continuously subjecting one end thereof to a pressure less than working cylinder pressure but in excess of atmospheric pressure, and means for alternatively subjecting the other end thereof throughout nearly complete piston 45 travels in opposite directions to cylinder pressure and to atmospheric pressure.

3. In a motor, in combination, a cylinder, a piston reciprocable therein, means for continuously venting one end of said cylinder, and means for controlling admission and exhaust with respect to the opposite end of said cylinder including a valve operative in opposite positions to effect the admission and exhaust functions, means for moving said valve in one direction by motor back pressure, and means for moving said valve in the opposite direction by cylinder pressure, said last-mentioned means having associated therewith means for trapping the throwing pressure during the major portion of piston movement in one direction.

4. In a motor, in combination, a cylinder, a piston reciprocable therein, means for continuously venting one end of said cylinder, and means for controlling admission and exhaust with respect to the opposite end of said cylinder including a valve operative in opposite positions to effect the admission and exhaust functions, means for moving said valve in one direction by motor back pressure, and means for moving said valve in the opposite direction by cylinder pressure.

sure, said last-mentioned means having associated therewith means, including a distributing-valve-controlled check valve, for trapping the throwing pressure during the major portion of piston movement in one direction.

5. In a motor, in combination, a cylinder, a piston reciprocable therein, means for admitting and exhausting motive fluid with respect to one end of the cylinder, and means for substantially 10 freely venting the other end of the cylinder to atmosphere during normal movements of said piston by the motive fluid supplied thereto and for automatically cushioning abnormal movements of said piston in a working direction including means for connecting the other end of the cylinder to atmosphere providing respectively 15 different areas of communication with the atmosphere automatically in dependence upon the rate of piston movement, the larger area adequate to provide for substantially unrestricted discharge of air during normal working piston movements.

6. In a motor, in combination, a cylinder, a piston reciprocable therein, means for admitting 20 and exhausting motive fluid with respect to one end of the cylinder, and means including a valve governed by fluid displaced by the piston for connecting the other end of the cylinder to atmosphere providing different areas of communication 25 with the atmosphere automatically in dependence upon the rate of piston movement, the larger area such as to preclude the opposition of any substantial pressure to piston movement during normal working strokes of the latter and 30 said valve movable to close said larger area of communication.

7. In a motor, in combination, a cylinder, a piston reciprocable therein, means for admitting and exhausting motive fluid with respect to one 40 end of the cylinder, and means for substantially freely venting the other end of the cylinder to atmosphere during normal movements of said piston by the motive fluid supplied thereto and for automatically cushioning abnormal movements of said piston in a working direction including means for connecting said other end of the cylinder to atmosphere including respectively 45 valved and unvalved passages and providing different areas of communication automatically in dependence upon the rate of piston movement, the larger area valve controlled and adequate to preclude material resistance of fluid pressure on the non-working side of the piston during normal working strokes of the latter.

8. In a motor, in combination, a cylinder, a piston reciprocable therein, means for admitting and exhausting motive fluid with respect to one end of the cylinder, and means for connecting the other end of the cylinder to atmosphere including 50 respectively valved and unvalved passages and providing different areas of communication, the latter the smaller, automatically in dependence upon the rate of piston movement, said valved passage having a controlling valve normally maintained open by gravity and governed by fluid displaced by the piston and providing an area of communication with the atmosphere sufficient to preclude substantial resistance to piston movement or building up of substantial fluid 55 pressure tending to close said valve during normal working piston movements.

9. In a motor, in combination, a cylinder, a piston reciprocable therein, means for admitting and exhausting motive fluid with respect to one 60 end of the cylinder, and means for controlling

over-movement of the piston in a working direction including a bypass for supplying pressure in advance of the piston and associated means for automatically checking displacement of fluid by said piston, upon abnormally rapid movement thereof, prior to the latter's attainment to said bypass.

10. In a motor, in combination, a cylinder, a piston therein, a distributing valve for controlling admission and exhaust of fluid relative to one end 10 of said piston, and valve-controlling means including cylinder-connected passages having controlling valves respectively carried and actuated by said distributing valve and controlling different ones of said cylinder-connected passages.

11. In a motor, in combination, a cylinder, a piston therein, a distributing valve for controlling admission and exhaust of fluid relative to one end 15 of said piston, and valve-controlling means including a plurality of cylinder-connected passages communicable with the same end of the valve and having controlling valves respectively carried and actuated by said distributing valve and controlling different ones of said cylinder-connected passages.

12. In a motor, in combination, a cylinder having a bypass passage intermediate its ends and an atmospheric communication for said bypass, a piston normally reciprocable in said cylinder short of either end of said by-pass, means for 30 effecting such normal reciprocation, and an automatic check valve controlling the degree of communication of said bypass with the atmosphere.

13. In combination, a motor comprising a cylinder with a piston normally reciprocable therein 35 in a predetermined path and having means for supplying working fluid to and venting it from one end of the cylinder, and means for substantially freely venting the other end of the cylinder to atmosphere during normal movements of said piston by the motive fluid supplied to the latter 40 and for checking piston movement should its normal path be exceeded by increasing the fluid resistance to piston movement, including means for providing a substantially free discharge of fluid from the non-working end of the cylinder during normal piston movement and for automatically, upon abnormal movements of the piston, reducing the freedom of displacement of fluid in advance of said piston while maintaining a predetermined limited freedom of displacement 45 of fluid.

14. In combination, a motor comprising a cylinder with a piston normally reciprocable therein 50 in a predetermined path, and means for automatically checking piston movement should said path be exceeded including means for increasing the fluid resistance to piston movement including both means for reducing the freedom of displacement of fluid in advance of said piston and means for increasing the quantity of fluid in advance thereof made effective on travel of said piston beyond the end of said predetermined path.

15. In combination, a motor comprising a cylinder with a piston normally reciprocable therein 55 in a predetermined path, said cylinder vented to provide for free air displacement in advance of the piston and preclude substantial fluid resistance upon said piston during normal working strokes of the latter and means for checking piston movement should said path be exceeded including means for increasing the fluid resistance to piston movement including means for precluding free displacement of fluid in advance of said piston, and means for increasing the quantity of 60

- fluid in advance thereof including means for conducting fluid from behind said piston to the space in advance thereof after the end of said predetermined path is reached.
- 5 16. In a motor, in combination, a cylinder, a piston reciprocable therein, and valve mechanism for said motor including a valve controlling both the admission and exhaust functions for said motor and having controlling means having a pressure area acting to move said valve to exhaust establishing position, and means for supplying pressure to said area and venting pressure therefrom respectively having communication with the cylinder bore at points widely spaced longitudinally of the latter, and having separate communications with said area each having a check valve associated therewith.
- 10 17. In a motor, in combination, a cylinder, a single-acting piston reciprocable therein, and valve mechanism for said motor including a valve controlling both the admission and exhaust functions for said motor and having a pressure area constantly subject to a pressure in excess of atmospheric and less than line pressure whereby said valve is biased constantly in one direction, and controlling means for said valve having a pressure area acting to move said valve in the opposite direction, and means for supplying pressure to said area to initiate such movement and vent pressure therefrom to permit reverse movement respectively having check-valve-controlled communication with the cylinder bore at points widely spaced longitudinally of the latter, the first at a point near the end of the working stroke 30 of the piston and the second at a point near the opposite end of the cylinder.
18. In a motor, in combination, a cylinder, a single-acting piston therein, and valve mechanism for said motor including a valve controlling both the admission and exhaust functions of the motor and having means for effecting movement thereof in one direction upon reduction in an opposing force, and means for providing such a force to effect the opposite valve movement including a pressure-fluid-actuated element and means associated therewith including a connection for transmitting pressure thereto after an initial movement of said element and ineffective until movement is started, and means for transmitting only a starting movement to said element ineffective as soon as substantial movement takes place.
- 40 19. In a motor, in combination, a cylinder, a piston reciprocable therein, means for continuously venting one end of said cylinder, and means for controlling admission and exhaust with respect to the opposite end of said cylinder including but a single distributing valve element, said valve element moved by motor back pressure to establish admission and having a reverse-movement-effecting pressure device having a plurality of piston-controlled connections with the cylinder bore and providing starting and throwing pressures, said starting pressure connection last uncovered by the piston on the working stroke of the latter.
- 45 20. In a motor, in combination, a cylinder, a piston reciprocable therein, means for continuously venting one end of said cylinder, and means for controlling admission and exhaust with respect to the opposite end of said cylinder including but a single distributing valve element, said valve element moved by motor back pressure to establish admission and having a reverse-movement-effecting pressure device having a plurality of piston-controlled check-valved connections
- 55 with the cylinder bore and providing starting and throwing pressures, said starting pressure connection last uncovered by the piston on the working stroke of the latter.
21. In a motor, in combination, a cylinder, a single-acting piston reciprocable therein, and valve mechanism for said motor including a valve controlling both the admission and exhaust functions of said motor and controlling means for said valve having a pressure area acting to move said valve in one direction, and means for supplying pressure to said area and venting pressure therefrom respectively having check-valve-controlled communications with the cylinder bore at points widely spaced longitudinally of the latter, the first at a point uncovered by the piston near the end of the working stroke of the latter and the second at a point near the opposite end of the cylinder.
- 25 22. In a motor, in combination, a cylinder, a single-acting piston reciprocable therein, and valve mechanism for said motor including a valve controlling both the admission and exhaust functions of said motor and controlling means for said valve having a pressure area acting to move said valve in a direction to interrupt admission and establish exhaust, and means for supplying pressure to said area and venting pressure therefrom respectively having check-valve-controlled communications with the cylinder bore at points widely spaced longitudinally of the latter, the first at a point uncovered by the piston near the end of the working stroke of the latter and the second at a point near the opposite end of the cylinder.
- 30 23. In a motor, in combination, a cylinder, a single-acting piston reciprocable therein, and valve mechanism for said motor including a valve controlling both the admission and exhaust functions of said motor and controlling means for said valve having a pressure area acting to move said valve in a direction to interrupt admission and establish exhaust, and means for supplying pressure to said area and venting pressure therefrom respectively having check-valve-controlled communications with the cylinder bore at points widely spaced longitudinally of the latter, the first at a point uncovered by the piston near the end of the working stroke of the latter and the second at a point near the opposite end of the cylinder, said valve having means for moving the same in the opposite direction including a second pressure area and means for subjecting the same constantly to a pressure intermediate supply pressure and atmospheric pressure.
- 35 24. In a motor, in combination, a cylinder, a piston reciprocable therein, means for continuously venting one end of said cylinder, and means for controlling admission and exhaust with respect to the opposite end of the cylinder including a valve performing both admission and exhaust functions and having associated throwing means including means for continuously exerting in one direction a pressure on said valve adequate to throw the same in said direction when unopposed, and means for exerting on said valve throughout nearly the entire piston travel in one direction a superior pressure acting in opposition to and overcoming said first mentioned pressure, and for maintaining said valve, throughout nearly the entire piston travel in the opposite direction, free from such superior pressure.
- 40 25. In a motor, in combination, a cylinder, a piston reciprocable therein, means for continuously venting one end of said cylinder, and means

- for controlling admission and exhaust with respect to the opposite end of said cylinder including a valve operative in opposite positions to effect the admission and exhaust functions,
- 5 means for moving said valve in one direction by a pressure less than cylinder working pressure, and means for moving said valve in the opposite direction by a higher pressure, said last mentioned means having associated therewith means for trapping the throwing pressure during the major portion of piston movement in one direction.
26. In a motor, in combination, a cylinder, a single acting piston therein, and valve mechanism for said motor including a valve controlling both
- 15 the admission and exhaust functions of the motor and having means for effecting movement thereof in one direction on reduction in an opposing force, and means for providing such a force to effect the opposite valve movement including a surface sub-
- 20 jectable to fluid pressure, means associated with said surface including a valve-controllable connection for transmitting pressure thereto after an initial movement of said surface but ineffective until such movement takes place, and valve-
- 25 controllable means for transmitting only a starting movement to said surface ineffective as soon as substantial movement takes place.
27. In combination, a motor comprising a cylinder with a piston normally reciprocable therein
- 30 in a predetermined path, means for controlling distribution of pressure fluid with respect to one end of said cylinder, a vent for providing for free air displacement in advance of the piston during normal working strokes of the latter and overrun
- 35 by said piston on the latter's exceeding its normal path of movement by a predetermined amount, and means for preventing free venting of said cylinder should said piston exceed its normal stroke, said last mentioned means including
- 40 means operative on a predetermined increase in cylinder pressure adjacent said vent to partially close said vent.
28. In combination, a motor comprising a cylinder with a piston normally reciprocable therein
- 45 in a predetermined path, and means for checking piston movement should said path be exceeded including means for conducting fluid from behind said piston to the space in advance thereof, a vent for providing for free air displacement in advance of said piston during normal working strokes of the latter and overrun by said piston when the normal working stroke of said piston is exceeded by a predetermined amount, and means associated with said vent for preventing free venting

of said cylinder including means operative on a predetermined increase of cylinder pressure adjacent said vent to partially close said vent.

29. In combination, a motor comprising a cylinder with a piston normally reciprocable therein in a predetermined path, means for admitting and exhausting motive fluid with respect to one end of the cylinder, and means for connecting said cylinder to atmosphere and overrun by said piston when the normal stroke of the piston is exceeded by a predetermined amount, said last mentioned means including a valve governed by pressure differentials between atmosphere and said cylinder and providing different areas of communication with the atmosphere automatically in accordance with said pressure differentials.

30. In combination, a motor comprising a cylinder with a piston normally reciprocable therein in a predetermined path, means for admitting and exhausting motive fluid with respect to one end of the cylinder, and means for connecting said cylinder to atmosphere which means is overrun by said piston when the normal stroke of the piston is exceeded by a predetermined amount,

20 said last mentioned means including valved and unvalved passages and providing different areas of communication automatically in dependence upon pressure differentials between atmosphere and said cylinder, the larger area adequate to

25 preclude material resistance to fluid pressure on the non-working side of the piston during normal working strokes of the latter.

31. In combination, a single-acting expansible-chamber motor including a reciprocable piston

35 and a cylinder, the latter materially elongated beyond the normal range of piston movement, said cylinder having associated with the inactive end thereof cushion means for controlling piston speed, said cushion means including in communication with said cylinder at a point beyond the normal stroke limit of the motor piston but overrun by the piston upon abnormal strokes, means for providing a continuous limited venting of the inactive end of said motor, and means for providing a larger communication between said inactive end and the atmosphere, said last mentioned means having a controlling valve maintained in a position to preclude at normal piston speeds the offering of material resistance to motor piston

40 movement but movable, upon a higher rate of

45 piston movement in a working direction, in a closing direction.
